REMOTE INSTRUMENT AND CONTROL FOR BATTERY CHARGER

Eugene B. Raymond, 4041 West Grove, Skokie, Ill.

Filed Sept. 7, 1965, Ser. No. 86,880

Term of patent 7 years

(Cl. D26—15)

FIG. 1 is a perspective view of a remote instrument and control for a battery charger showing my new design;

FIG. 2 is a perspective view of the opposite side thereof as viewed from the rear;

FIG. 3 is a view similar to FIG. 1 but showing the parts in different position.

I claim:

The ornamental design for remote instrument and control for battery charger, as shown and described.
